UNITED STATES PATENT OFFICE

FREDERICK T. THEBERT, OF BESSEMER, MICHIGAN.

TONGS.

1,149,476.

Specification of Letters Patent.

Patented Aug. 10, 1915.

Application filed December 23, 1914. Serial No. 878,780.

To all whom it may concern:

Be it known that I, FREDERICK T. THEBERT, a citizen of the United States, residing at Bessemer, in the county of Gogebic and 5 State of Michigan, have invented certain new and useful Improvements in Tongs, of which the following is a specification, reference being had to the accompanying drawings.

10 This invention relates to new and useful improvements in tongs and more particularly to what will be hereinafter known as coal tongs, the main object of the present invention being the provision of a pair of 15 tongs of the above character which is particularly adapted for use in handling briquet coal and for various other similar purposes.

Another object of the present invention is the provision of a device of the above character which will possess advantages in points 20 of efficiency and durability, is inexpensive to manufacture and, at the same time, is simple in construction and operation.

With the above and other objects in view, 25 the invention consists in the novel features of construction, combination and arrangement of parts as will be hereinafter referred to and more particularly pointed out in the specification and claims.

30 In the accompanying drawing forming a part of this application, Figure 1 is a side elevation of a pair of coal tongs constructed in accordance with my invention. Fig. 2 is a top plan view illustrating the application of the same. Fig. 3 is a detail perspective view of one of the tong members; and Fig. 4 is a detail perspective view of the opposite tong member.

In the construction of my improved tongs, 40 I provide two pivoted members, each consisting of a single piece of wire, one of said members having its intermediate portion provided with an elongated loop 1 which is preferably used for the reception of the 45 fingers of a hand. The ends of the wire are then twisted to form a shank 2. After the shank 2 has been formed, the ends are then extended in opposite directions to form alined pivot arms 3 and thence extended to 50 form arcuate jaws 4.

The opposite section consists of a single length of wire substantially the same weight as the first section and is bent upon itself at its intermediate portion to form a loop 5, 55 preferably a thumb loop. The ends of the

wire are then twisted to form a shank 6, which is somewhat longer than the shank 2, but the loop 5 is not as long as the loop 1. The ends of the wire of the second section are curved in opposite directions from the shank 6, as shown at 7, thence bent upon themselves to form the eyes 8, which are mounted for pivotal movement upon the arms 3 of the opposite section. The wire after being looped to form the eyes 8, is then arcuately curved to form the jaws 9 which are arranged in opposed relation with the members 4. From this it will be apparent that upon moving the handles 1 and 5 toward or away from each other, the jaws 4 and 9 will be moved toward or away from each other, whereby to grasp an object between the same or release it, when desired.

From the foregoing description, taken in connection with the accompanying drawing, 75 it will be readily apparent that I have provided a simple and durable pair of tongs, which are preferably used for handling briquet coal and it will be noted that in using the tongs, the thumb is arranged within the loop 5, while the fingers of the hand are arranged within the loop 1. From this it will be seen that the opposed jaws 4 and 9 can be readily actuated toward or away 80 from each other to grasp or release the coal or other object to which they may be applied. It will be noted that by having the eyes 8 pivotally mounted upon the arms 3, inward of the jaws 4, it will securely hold 85 the two sections together and prevent them from becoming accidentally disconnected.

It will also be noted that my improved tongs can be manufactured and placed upon the market at a comparatively low cost.

While I have shown and described the 95 preferred form of my invention, it will be obvious that various changes in the details of construction and in the proportions may be resorted to for successfully carrying my invention into practice, without sacrificing 100 any of the novel features or departing from the scope of the invention, as defined by the appended claims.

Having thus described this invention, 105 what I claim is:—

1. Tongs including pairs of jaws, each pair formed from a single length of wire, the wire forming one pair of jaws being bent to provide a pair of spaced eyes, the remaining pair of jaws being offset at their 110

inner ends to provide pintles, said pintles being pivotally mounted within the eyes of the first-named jaws.

2. Tong including lengths of wire, each being twisted upon itself to provide a shank, the ends of one of the wires being laterally curved in opposite directions and then bent to provide aligned eyes, said ends being then extended to provide parallel jaws, the ends ¹⁰ of the other wire being bent in opposite directions to provide pintles, the ends being

then extended to form jaws which coact with the first-named jaws, the pintles being disposed within the eyes of the first-named jaws.

In testimony whereof I hereunto affix my signature in the presence of two witnesses.

FRED. T. THEBERT.
